AMPLITUDE MODULATION LIMITER
CIRCUITSeymour Hunt, Flushing, N. Y., assignor to Radio
Corporation of America, a corporation of Del-
aware

Application August 22, 1941, Serial No. 407,889

14 Claims. (CL 178—44)

My present invention relates to limiter circuits, and more particularly to an amplitude limiter circuit adapted for use in receivers of frequency, or phase, modulated carrier waves.

One of the main objects of my present invention is to provide a multi-grid tube which is arranged in a limiter circuit, used in a receiver of frequency, or phase, modulated carrier waves; the modulated carrier waves being impressed upon at least one of the control grid circuits of the tube including a time constant network which has a value which is short compared to the shortest audio period and is long compared to the wave period whereby amplitude modulation effects existing on the modulated carrier wave are minimized, a second one of the control grids of the tubes being connected to the time constant network so as to exert a further limiting action on the output amplitude of the tube.

Another important object of the invention is to utilize in place of cascaded amplitude limiters known in the prior art, a single tube provided with at least two spaced control grids, at least one of the control grids having frequency, or phase, modulated carrier waves applied thereto, and both grids having applied to them fast-acting control voltage for eliminating amplitude modulation effects which may exist on the modulated carrier wave.

Still other objects of my invention are to improve limiter circuits for frequency modulated carrier wave receivers, and more particularly to provide a multi-electrode limiter tube which is not only reliable and efficient in operation, but, also, is economically and effectively assembled in frequency modulation receivers.

The novel features which I believe to be characteristic of my invention are set forth in particularity in the appended claims; the invention itself, however, as to both its organization and method of operation will best be understood by reference to the following description taken in connection with the drawing in which I have indicated diagrammatically several circuit organizations whereby my invention may be carried into effect.

In the drawing:

Fig. 1 illustrates an embodiment of the invention.

Fig. 2 shows a modification.

Referring, now, to the accompanying drawing, wherein like reference characters in the two figures designate similar circuit elements, the numeral 1 designates the multi-grid limiter tube

which may be one of the 6A8 type. The tube is provided with a cathode 2 and a first control grid 3, a second control grid 4 and a plate, or output, electrode 5. The control grid 4 is located between a pair of positively biased screen grid electrodes, the lead to the screen grids being by-passed to ground for carrier frequencies. The tube element between grid 3 and the screen grid is an unused electrode of the tube. The numeral 6 denotes the tuned input circuit which is connected between the control grid 3 and the grounded cathode 2. In the low potential side of the input circuit there is included a series resistor 7 which is shunted by condenser 8. The plate 5 is connected to the positive terminal of the direct current source through the output transformer primary winding 9 which is shunted by condenser 10. The primary circuit 9—10 is tuned to the same center frequency of the incoming modulated carrier waves as is input circuit 6. The grid 4 is connected to an adjustable tap 11, which is slidable along resistor 7, through a resistor 12 which is shunted by condenser 13. The network 12—13 has the same time constant value as the network 7—8.

The input circuit 6 may be coupled to a preceding resonant circuit 6'. The latter may be located in the plate circuit of the final intermediate frequency (I. F.) amplifier tube, or it 30 may be located in the plate circuit of the converter tube. This will be feasible where the receiver is of the superheterodyne type, and, of course, it will be understood by those skilled in the art that the latter type of receiver is substantially universally employed in receiving frequency modulated carrier waves. Of course, the frequency modulated (FM) carrier waves may be applied directly to an amplifier tuned to the center frequency of the carrier waves, and in 35 such case amplified waves will be applied to the input circuit 6.

The presently assigned FM band covers a range of 42 to 50 megacycles (mc.), and the permissible FM channel width is 200 kilocycles (kc.). Each 40 of circuits 6—6 and 9—10 would be tuned to the center, or mean, frequency of the FM waves. Where the stage preceding the circuit 6' is the I. F. amplifier, then the aforesaid tuned circuits will be tuned to the operating I. F. value which 45 may be a frequency chosen from a range of 2 to 4 mc.

The function of the limiter, of course, is to minimize amplitude modulation effects which arise due to tube noises, fading, or the effect of 50 prior resonant circuits on the transmitted FM

wave energy. Regardless of the cause, it is necessary to insure the impression upon the FM detector of modulated carrier waves which have no amplitude modulation components. Since the function of the FM detector is to produce modulation signal voltages corresponding to the modulation signal voltage applied to the carrier wave at the transmitter, it is essential that at the detector input circuit there be no variation in the amplitude of the carrier. As is well known the modulation signals appear on the FM carrier wave as a frequency deviation of the transmitter carrier frequency. In the past it has been proposed to use cascaded limiter circuits. Such proposals require extra circuit elements. By providing a dual control over the electron stream within a single tube, it is possible to use a single tube and secure more efficient limiting action which can function at relatively low carrier input levels. This is a further advantage over prior limiters, in that considerable carrier amplification has been thought necessary prior to impression of the waves upon the limiter network.

Considering the mode of operation of the limiter tube, it is pointed out that the cathode, control grid 3 and plate 5 act like a low mu section, whereas the cathode, control grid 4 and plate 5 act in the manner of a high mu section. Accordingly, the limiter voltage developed across resistor 7 is applied at a predetermined magnitude to the control grid 4 so as to produce a limiter characteristic which is substantially flat above a relatively small carrier input level. It is pointed out that there is developed across resistor 7, by virtue of the time constant network 7-8, a fast-acting automatic volume control (AVC) voltage. The network 12-13 is chosen so as to have a time constant which is short compared to the shortest audio period and long compared to the carrier wave period. Hence, the control grid 4 has applied to it fast-acting AVC bias which provides a final flattening control over the limiter characteristic should there otherwise be a tendency for the characteristic to rise. Of course, the tap 11 may be adjusted to any desired portion of resistor 7 so that a predetermined value of limiter voltage may be applied to control grid 4. It will be noted, furthermore, that the FM waves are applied solely to control grid 3, while both grids 3 and 4 have the fast-acting limiting voltage applied thereto.

The limited FM waves developed in the output circuit 10-9 are impressed upon the input circuit 20 of the FM detector. It is not believed necessary to show the nature of the detector because those skilled in the art are fully aware of the various types of devices that may be employed to derive the modulation voltage from the limited FM waves. Besides providing the limiting operation at low carrier levels, this circuit functions to initiate limiting action relatively quickly and at a rate which is faster than would be the case were control grid 4 not employed. Here, again, this is an advantage over cascaded limiters. In effect the tube acts as a higher mu tube for the quick acting AVC or limiting voltage, than for the FM waves. Above a certain input level of the FM waves the output of tube 1 could be made to decrease, if such a characteristic were desired.

The invention is not limited to applying the FM waves to but one of the control grids, since the modulated carrier waves may be applied to both of the control grids and the limiter voltage applied to only one of the control grids. In this

latter case there is provided the opportunity of preventing an otherwise drooping characteristic which is often encountered in the usual type of limiter circuit using but one control grid. Thus,

5 in Fig. 2 there is shown a modification of the arrangement of Fig. 1, wherein the control grid 3 is connected to the tuned input circuit 6 in the same manner as Fig. 1. However, control grid 4 is connected to an adjustable tap 11' through a 10 direct current blocking condenser 30. The tap 11' may be adjusted to any desired point along the coil of input circuit 6 so that the relative magnitudes of the FM waves applied to grids 4 and 3 may be easily adjusted.

15 The grid 4 is further connected to the adjustable tap 11 through a series path including the carrier frequency choke coil 49 and the biasing voltage source 41. The voltage source 41 is poled so as to render grid 4 normally negative with respect to the cathode. By adjusting the tap 11 to any desired point along resistor 7 the magnitude of the limiter voltage applied to grid 4 will be controlled. It will, therefore, be seen that in the arrangement in Fig. 2 there are provided controls 11' and 11 which may be adjusted to determine the magnitude of the FM waves and the magnitude of the limiter voltage which is to be applied to grid 4. In this way the resultant limiter characteristic may be varied over a con-

20 siderable range so as to vary in different manners with the variation in carrier amplitude level. The expression "angle modulated" when used in the claims in connection with the nature of the modulation of carrier wave energy generically 25 signifies frequency modulation, phase modulation or hybrids thereof.

30 While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

35 45 What I claim is:

1. In combination, in an amplitude modulation limiter stage, a tube provided with at least a cathode, an output electrode and a pair of intermediate control grids, an output circuit connected to the output electrode, a source of angle modulated carrier waves connected between at least one of the intermediate grids and the cathode, means connecting the second intermediate grid to a point on an input circuit including said first intermediate grid and cathode, and a separate time constant network being connected in circuit with each of said intermediate grids, each of said time constant networks having a value short compared to the highest modulation frequency and long compared to the carrier wave.

to the second grid thereby to augment said limiting action.

3. In combination, an electron discharge tube provided with a cathode, a plate, and at least two control grids, an input circuit tuned to the center frequency of the frequency modulated carrier waves, means connecting the cathode and one of the control grids to said input circuit, said means including a fast-acting time constant network, means providing an adjustable direct current voltage connection between the second control grid and a desired point on said time constant network, and additional means providing an adjustable modulated carrier wave connection between the said input circuit and said second control grid.

4. In combination with a source of angle modulated carrier waves, a limiter stage for minimizing amplitude modulation effects in the carrier waves, said limiter including a multi-grid electron discharge tube, a resonant circuit coupling said source to the cathode and one of the grids of said tube, said resonant circuit including a resistance-condenser network having a relatively short time constant value for developing a negative direct current limiting voltage, and a direct current voltage connection between a point on said time constant network and a second grid of said tube whereby the same limiting voltage developed across said time constant network is applied to said second grid thereby to augment said minimizing action.

5. In combination with a source of angle modulated carrier waves, a limiter stage for minimizing amplitude modulation effects in the carrier waves, said limiter including a multi-grid electron discharge tube, a resonant circuit coupling said source to the cathode and one of the grids of said tube, said resonant circuit including a resistance-condenser network having a relatively short time constant value, and a direct current voltage connection between a point on said time constant network and a second grid of said tube whereby limiter voltage developed across said time constant network is applied to said second grid, said direct current voltage connection including a time constant network having a relatively short time constant value.

6. In combination, a tube provided with at least a cathode, an output electrode and a pair of intermediate control grids, an output circuit connected to the output electrode, a source of angle modulated carrier waves connected to at least one of the intermediate grids, means connecting the second intermediate grid to a point on an input circuit including said first intermediate grid, separate time constant networks being connected in circuit with each of said intermediate grids, each of said time constant networks having a relatively short value.

7. In combination, an electron discharge tube provided with a cathode, a plate, and at least two control grids, an input circuit tuned to the mid-frequency of applied frequency modulated carrier waves, a fast-acting time constant network connecting the cathode and one of the control grids to said input circuit for developing a negative direct current voltage, means providing an adjustable direct current voltage connection between the second control grid and a desired point on said time constant network for applying a predetermined fraction of the same negative voltage to said second grid.

8. In combination, an electron discharge tube 75 means connecting the cathode and one of the control grids to said input circuit, said means consisting of resistance and capacity acting as a fast-acting time constant network, means providing an adjustable direct current voltage connection between the second control grid and a desired point on said time constant network, and additional means providing an adjustable modulated carrier wave connection between the said input circuit and said second control grid.

provided with a cathode, a plate, and at least two control grids, means connecting the cathode and one of the control grids to a modulated carrier wave input circuit, said means including a fast-acting time constant network, means providing an adjustable direct current voltage connection between the second control grid and a desired point on said time constant network, and additional means providing an adjustable modulated carrier wave connection between the said input circuit and said second control grid.

9. In combination with a source of angle modulated carrier waves, a limiter including a multi-grid electron discharge tube, a circuit tuned to the modulated wave center frequency coupling said source to the cathode and one of the grids of said tube, said resonant circuit including a resistance-condenser network having a relatively short time constant value for developing a negative direct current limiting voltage, and a direct current voltage connection between a point on said time constant network and a second grid of said tube whereby the same limiting voltage developed across said time constant network is applied to said second grid thereby to augment limiting action.

10. In combination, in an amplitude modulation limiter stage, a tube provided with at least a cathode, an output electrode and a pair of intermediate control grids arranged in the electron stream from the cathode to output electrode, an output circuit connected to the output electrode, a source of angle modulated carrier waves connected between one of the intermediate grids and the cathode, means connecting the second intermediate grid to a point in an input circuit including said first intermediate grid and cathode, separate time constant networks being connected in circuit with each of said intermediate grids, each of said time constant networks having a value short compared to the shortest modulation frequency and long compared to the carrier wave.

11. In combination, an electron discharge tube provided with a cathode, a plate, and at least two control grids, an input circuit tuned to the center frequency of the frequency modulated carrier waves, means connecting the cathode and one of the control grids to said input circuit, said means comprising resistance and shunt capacity acting as a fast-acting time constant network for developing a negative direct current voltage, means providing an adjustable direct current voltage connection between the second control grid and a desired point on said time constant network for applying a predetermined portion of the same negative voltage to the second grid.

12. In combination, an electron discharge tube provided with a cathode, a plate, and at least two control grids, an input circuit tuned to the center frequency of frequency modulated carrier waves, means connecting the cathode and one of the control grids to said input circuit, said means consisting of resistance and capacity acting as a fast-acting time constant network, means providing an adjustable direct current voltage connection between the second control grid and a desired point on said time constant network, and additional means providing an adjustable modulated carrier wave connection between the said input circuit and said second control grid.

13. In combination with a source of angle modulated carrier waves, a limiter stage for minimizing amplitude modulation effects in the car-

rier waves, said limiter including a multi-grid electron discharge tube, a resonant circuit coupling said source to the cathode and one of the grids of said tube, said resonant circuit including a resistance-shunt condenser network having a relatively short time constant value for developing a negative direct current limiting voltage, and a direct current voltage connection between a point on said time constant network and a second grid of said tube whereby limiting voltage developed across said time constant network is applied to said second grid.

14. In combination with a source of angle modulated carrier waves, a limiter stage for minimizing amplitude modulation effects in the carrier waves, said limiter including a multi-grid

5 electron discharge tube, a resonant circuit tuned to the modulated wave center frequency coupling said source to the cathode and one of the grids of said tube, said resonant circuit consisting of a resistor and shunt condenser network having a relatively short time constant value, a direct current voltage connection between a point on said time constant network and a second grid of said tube whereby limiter voltage developed across said time constant network is applied to said second grid, said direct current voltage connection including a second time constant network having a relatively short time constant value.
